UNITED STATES PATENT OFFICE

JOSEPH J. MARESH, OF TERRELL, TEXAS

PHOTOGRAPHIC PRINTING MACHINE

Application filed March 5, 1931. Serial No. 520,897.

This invention relates to a photographic printing machine and has for its primary object to provide, in a manner as hereinafter set forth, a machine of such class which will print successively a photographic view and a border therefor without manually handling or adjusting the object upon which the print and border are made.

A further object of the invention is to provide a machine of the character aforesaid which includes a movable suction head for holding an object to be printed in position with respect to a negative and border applying means successively; which includes means associated with the head for automatically stamping a number or the like on the object; and which includes circuit closing means operated by the movement of the head for energizing a suction element and a printing lamp successively.

With the foregoing and other objects in view, the invention consists of the novel construction, combination and arrangement of parts as hereinafter more particularly described, and as illustrated in the accompanying drawing wherein is shown an embodiment of the invention, but it is to be understood that the description and drawings are to be taken as illustrative and that the invention is intended to be limited only by the scope of the claims hereunto appended.

In the accompanying drawings wherein like numerals are employed to designate like parts throughout the several views:

Figure 1 is a side elevation of a machine in accordance with this invention.

Figure 2 is a front elevation thereof.

Figure 3 is a vertical section therethrough showing the arrangement of the parts at the beginning of the printing operation and further showing diagrammatically the electrical circuits employed in connection with the operation of the machine.

Figure 4 is a fragmentary view similar to Figure 3 showing the position of the parts during the application of the border to the printed object.

Figure 5 is a sectional plan of the machine with the parts arranged as in Figure 4.

Figure 6 is a sectional rear elevation of

the machine with the suction element and motor for operating the same removed.

Figure 7 is a fragmentary sectional detail illustrating the numbering device carried by the printing head.

Referring to the drawings in detail, the numeral 1 indicates generally a relatively tall housing, and the numeral 2 indicates generally a relatively short housing arranged forwardly of the housing 1. The housings 1 and 2 are provided with a common bottom wall 3. The housing 1 includes a pair of side walls 4, a rear wall 5, a top wall 6, a front wall section 7 depending from the top wall 6, and a front wall section 8 extending upwardly from the bottom wall 3. The front wall section 7 is arranged forwardly of the front wall section 8 with the lower edge of the section 7 arranged in a materially higher plane than the upper edge of the section 8. The side walls 4 are recessed as indicated at 9 to a point substantially in vertical alignment with the wall section 8. Extending from the wall section 8 to the rear wall 5 is a horizontal partition 10, and extending from the partition 10 to the bottom wall 3 is a vertical partition 11. The partitions 10 and 11, in conjunction with the walls of the housing 1 divides the latter into what will be termed a printing head compartment 11, a motor compartment 12, and a lamp compartment 13. Disposed within the compartment 12 is a motor 14 for operating a suction element indicated generally at 15, the motor 14 being adapted for connection with an electrical socket 16. Disposed within the compartment 13 is a lamp 17 which is connected with an electrical socket 18.

The housing 2 includes a pair of side walls 19, a front wall 20, and a top wall 21 which extends in continuation of the horizontal partition 10. The front wall section 8 of the housing 1 also forms the rear wall of the housing 2. Disposed within the housing 2 is a horizontal partition 22 and a vertical partition 23 which divide the interior of the housing 2 into what will be termed a reflecting compartment 24 and a lamp compartment 25. Disposed within the lamp compartment 25 is a lamp 26 which is connected with an electrical socket 27. Disposed within the

100

compartment 24 is a supporting member 28 for a forwardly and upwardly inclined mirror 29 which is adapted to reflect upwardly light rays passing from the lamp 17 through an opening 30 in the wall section 8 adjacent to the mirror 29. The top wall 21 is formed with an opening 31 which extends entirely across the top of the compartment 24, and which further extends substantially across the top of the compartment 25. The partition 10 is provided with a pair of ventilating openings 32 for the compartment 13.

Mounted on the wall 21 and partition 10 is a stationary frame 33, upon the side members of which is mounted a sliding frame 34. The side members of the frame 34 are longitudinally grooved as indicated at 35 to receive the upper portion of the side members of the frame 33 therein and to lower the end members of the frame 34 in order to bring the same into alignment with the end members of the frame 33 whereby the end members of the frame 33 provide stops for limiting the sliding movement of the frame 34. The frame 34 is manually slideable and is provided at its forward end with an upstanding lug 36 for conveniently operating the frame. Carried by the frame 34 is a glass carrying frame 37 which is maintained in position by a series of lugs 38 projecting upwardly from the frame 34. The frame 37 is provided with a glass 39. Carried by the rearward portion of the frame 37 is a border forming mask 40 which is disposed in alignment with the reflecting compartment 24 when the frame 34 is disposed in its extreme forward position. Hingedly mounted at the forward end of the frame 37 is a skeleton mask 41 which is in alignment with the reflecting compartment 24 when the frame 34 is disposed in its extreme rearward position.

Extending through an opening 42 in the partition 10 is a curved suction pipe 43, the rearward end of which is in communication with the suction element 15, and the forward end of which is provided with a hollow printing head 44. The suction pipe 43 is pivotally mounted on a bracket 45 mounted on the partition 10. Extending across the bottom of the head 44 is a flexible pad 46, and extending through the pad 46 and bottom of the head 44 are a plurality of openings 47. Projecting upwardly from the head 44 is a lug 48 to which is pivotally connected one end of a link 49. The opposite end of the link 49 is pivotally connected with a crank arm 50 which extends through a slot 50' in the wall section 7 and is adjustably mounted on an operating shaft 52 extending transversely of the housing 1 and journaled in the side walls 4 of the latter. The shaft 52 is provided at one end thereof with a crank handle 53 for operating the shaft. Adjustably mounted on the shaft 52 is a crank arm 51 which extends between side flanges 54 on a

rearwardly extending bar 55. The flanges 54 project forwardly from the upper face of the bar 55 whereby the bar is provided at its forward end with a recess 56. The forward ends of the flanges 54 are pivotally connected with the crank arm 51 in spaced relation to the rearward end of the latter. Carried by the rearward end of the bar 55 is a rod 57 which extends downwardly through the opening 42 and is pivotally connected at its lower end to a lever 58 which is provided at its forward end with a shutter 59 normally closing the opening 30 through the wall section 8. The lever 58 is pivotally mounted at its rearward end on a post 60 projecting upwardly from the bottom wall 3. The head 44 is normally maintained in the elevated position shown in Figure 3 by means of a spring 61, the respective ends of which are connected with the suction pipe 43 and a rod 62 carried by a pair of uprights 63 disposed within the housing 1 adjacent the side walls of the latter.

Projecting rearwardly from the shaft 52 is a crank 64 to which is pivotally connected the forward end of a link 65. The rearward end of the link 65 is pivotally connected with the upper end of a lever 66, the lower end of which is pivotally connected to a bracket 67 projecting forwardly from a post 68 extending upwardly from the partition 10 adjacent a rearward corner of the housing 1. The lever 66 and bracket 67 are formed of electrical conducting material and the link 65 is formed of insulating material. Secured to the forward face of the post 68 is an insulating base 69 which is provided with a pair of spaced contact members 70 and 71. The contact members 70 and 71 are formed of resilient material with the member 71 arranged above the member 70.

Carried by the head 44 is a numbering device which includes a lever 72 pivotally mounted intermediate its ends on a bracket 73 projecting upwardly from a platform 74 formed on one side of the head 44. Projecting laterally from the lever 72 adjacent one end of the latter is a stationary stud 75 upon which is mounted a substantially U-shaped bracket 76. Rotatably mounted on the stud 75, between the side members of the bracket 76, are a pair of flanged discs 77 which are maintained in spaced relation by means of a washer 78 interposed therebetween and rotatably mounted on the stud 75. Extending around the flanges on the discs 77 and the closed end of the bracket 76 are a pair of endless, indicia carrying bands 79. Adjacent the bracket 73, rearwardly of the latter, the platform 74 is provided with an adjusting screw 80 for limiting the downward movement of the rearward end of the lever 72. The lever 72 is normally maintained in engagement with the screw 80 by means of a spring 81, the respective ends of which are

connected with the upper end of the bracket 73 and with the lever 72 at a point in spaced relation to the bracket 73 forwardly of the latter. The lever 72 is provided at its rearward end with a downward projection 82 which engages a stud 83 projecting upwardly from the rearward end member of the sliding frame 34. Slidably mounted on the bottom wall of the head 44, and confined within a recess 84 in the lower face of the platform 74, is a tray 85 upon which is mounted an ink pad 86. Pivotally connected with the rearward end of the tray 85 is an angular rod 87, the rearward end of which is pivotally connected with the post 68. When the head 44 is in its elevated position, the ink pad 86 is moved forwardly by the rod 87 for supplying ink to the indicia carrying bands 79. When the head 44 is in its lowered position 20 the tray 86 is moved rearwardly by the rod 87 to permit a downward movement of the bracket 76 when the projection 82 is brought into engagement with the stud 83. The bottom wall of the head 44 and the pad 46 are 25 formed with an opening 88 in vertical alignment with the bracket 76.

The electrical circuits for the machine include a pair of conductors 89 and 90 which are adapted for connection with a source of 30 electrical supply, and which are further connected with the terminals 91 for the lamp socket 27. The conductor 89 is connected by means of a branch 92 with the bracket 67, and the conductor 90 is connected by means of 35 branches 93 and 94 respectively with the motor socket 16 and lamp socket 18. The motor socket 16 is further connected by means of a conductor 95 with the contact member 70 while the lamp socket 18 is further connected by means of a conductor 96 with the contact member 71. It will be seen that the lamp 26 will be energized upon the passage 40 of current through the conductors 89 and 90 without energizing the motor 14 or lamp 17. The circuit for energizing the motor 14 is closed when the lever 66 is brought into contact with the contact element 70, while the circuit for energizing the lamp 17 is closed when 45 the lever 66 is brought into contact with the contact member 71.

In the operation of the machine current is admitted to the conductors 89 and 90 to energize the lamp 26 in order that the rays of the latter may be passed through the opening 50 31 to render the sliding frame 34 clearly visible. The frame 34 is then moved to its rearward position as illustrated in Figure 3. A negative or the like is then placed beneath the skeleton mask 41 and the object to be 55 printed, such as sensitized paper, is placed over the mask 41. The crank handle 53 is then utilized for rotating the shaft 52 which causes a lowering of the printing head 44 against the tension of the spring 61 until the flexible pad 46 is brought into engagement

with the object to be printed for holding the latter in position. Upon the downward movement of the head 44, the crank 64 moves the link 65 rearwardly whereby the lever 66 is first brought into contact with the contact member 70 for closing the circuit for the motor 14 whereby the suction element 15 is actuated for creating a suction through the head 44 and suction pipe 43. A further downward movement of the head 44 causes the lever 66 to be brought into engagement with the contact member 71 whereby the circuit for the lamp 77 is closed to energize the lamp. Coincidentally with the closing of the circuit for the lamp 17, the shutter 59 is raised to permit the passage of the rays from the lamp 17 through the openings 30, such rays being projected onto the mirror 29 and reflected therefrom through the opening 31. The shutter 59 is elevated when the rearward end of the angular bracket 50 is brought into engagement with the lower face of the bar 55 which causes the latter to be raised, carrying the rod 57 and lever 58 therewith.

After the printing of the negative as aforesaid, the crank handle 53 is released to permit the head 44 to be elevated by the action of the spring 61, such action breaking the circuit for the motor 14 and lamp 17. Owing to the suction within the head 44, the object being printed is raised with the head due to the openings 47 extending through the bottom of the head and the flexible pad 46. Upon the raising of the head, the sliding frame 34 is moved forwardly to the position shown in Figure 4, after which the shaft 52 is again actuated by means of the crank handle 53 which causes the head 44 to lower the printed object into position with respect to the border forming mask 40. The crank handle 53 is then again released to permit the upward movement of the head 44, after which the printed object may be removed therefrom.

Upon each downward movement of the head 44, the projection 82 on the lever 72 is brought into engagement with the stud 83 on the frame 34, whereby the lever 72 is swung on its pivot to bring the indicia carrying bands 79 into engagement with the object being printed for stamping a number or the like on the latter. Each time the head 44 is elevated, the tray 85 is slid forwardly by the rod 87 for supplying ink to the indicia carrying bands 79.

It is thought that the many advantages of a photographic printing machine in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. In a photographic printing machine, a source of light, a slidable element adapted to support a sensitized object to be photographically printed and including a negative retaining means and a border applying means, said element providing for respectively positioning the negative and border applying means relative to said source, a movable printing head for retaining the object in position relative to the negative when the latter is positioned relative to said source, suction means cooperating with said head for securing the object to the latter during the shifting of said element to position the border applying means relative to said source, and means operatively connected with said head to prevent the light rays from said source from passing to said element during the shifting of the latter.
2. In a photographic printing machine, a source of light, a slidable element adapted to support a sensitized object to be photographically printed and including a negative retaining means and a border applying means, said element providing for respectively positioning the negative and border applying means relative to said source, a movable printing head for retaining the object in position relative to the negative when the latter is positioned relative to said source, suction means cooperating with said head for securing the object to the latter during the shifting of said element to position the border applying means relative to said source, means operatively connected with said head for de-energizing said source during the shifting of said element, and means operatively connected with said head for immediately obstructing the passage of light rays from said source to said element upon the de-energizing of said source.
3. In a photographic printing machine, a source of light, a slidable element adapted to support a sensitized object to be photographically printed and including a negative retaining means and a border applying means, said element providing for respectively positioning the negative and border applying means relative to said source, a movable printing head for retaining the object in position relative to the negative when the latter is positioned relative to said source, suction means cooperating with said head for securing the object to the latter during the shifting of said element to position the border applying means relative to said source, means operatively connected with said head to prevent the passage of light rays from said source to said element during the shifting of the latter, and means operatively connected with said head for controlling said suction means.
4. In a machine for photographically printing a bordered picture, means for successively photographically printing the picture and border upon a sensitized object, said means including a light source and a shiftable element for successively positioning a negative and a border applying means relative to the light source, a shiftable printing head for successively retaining the object in position to have the picture and border printed thereon, a suction element in communication with said head for detachably securing said object thereto during the shifting of said element to position the border applying means relative to the light source, normally open circuits for said suction element and light source respectively, switch means operatively connected with said head for successively closing said circuits upon the movement of the head towards the sliding element to energize said suction element and light source and for successively opening said circuits when the head is moved away from said element to de-energize said suction element and light source, and means operatively connected with said head for immediately obstructing the passage of light rays from said source to said element upon the de-energization of said source.
5. In a machine for photographically printing a bordered picture, means for successively photographically printing the picture and border upon a sensitized object, said means including a light source and a shiftable element for successively positioning a negative and a border applying means relative to the light source, a shiftable printing head for successively retaining the object in position to have the picture and border printed thereon, a suction element in communication with said head for detachably securing said object thereto during the shifting of said element to position the border applying means relative to the light source, normally open circuits for said suction element and light source respectively, switch means operatively connected with said head for successively closing said circuits upon the movement of the head towards the sliding element to energize said suction element and light source and for successively opening said circuits when the head is moved away from said element to de-energize said suction element and light source, a shutter normally disposed within the path of travel of light rays passing from said source to said shiftable element, and means operatively connecting the shutter with said head to provide for the removal of the shutter upon the energizing of said source and to provide further for the return of the shutter to normal position coincidentally with the de-energizing of said source.
6. In a printing machine, a support for an object to be printed, a printing head movable in an arc toward and from said support, a numbering device carried by said head for contact with said object when the

head is moved toward the support, an inking
pad slidably connected with said head, and
a rod pivotally anchored at one end and
having its opposite end pivotally connected
5 with said pad for drawing the latter into
contact with the numbering device when the
head is moved away from the support.

In testimony whereof, I affix my signature
hereto.
